UNITED STATES PATENT OFFICE

LOUIS N. McCARTER, OF NORRISTOWN, PENNSYLVANIA, ASSIGNOR TO R. S. NEWBOLD & SON COMPANY, OF NORRISTOWN, PENNSYLVANIA, A CORPORATION OF PENNSYLVANIA.

FLANGING-MACHINE.

No. 825,285.

Specification of Letters Patent.

Patented July 3, 1906.

Application filed March 23, 1905. Serial No. 251,647.

To all whom it may concern:

Be it known that I, LOUIS N. McCARTER, a citizen of the United States, residing at Norristown, Pennsylvania, have invented certain

5 Improvements in Flanging - Machines, of which the following is a specification.

My invention relates to certain improvements in machines for flanging metal plates to form heads for boilers, drums, vats, and 10 other containers.

The object of my invention is to improve and simplify the construction of flanging-machines and to provide means whereby the parts can be driven by electric motors.

15 In the accompanying drawings, Figure 1 is a side view of my improved flanging-machine. Fig. 2^a is a sectional plan view on the line 2 2, Fig. 1. Fig. 2^b is a continuation of the plan view Fig. 2^a, showing one of the motors and the main driving-shaft. Fig. 3 is a sectional view of the flanging-roller carrier on the line 3 3, Fig. 4. Fig. 4 is a sectional view on the line 4 4, Fig. 3. Fig. 5 is a perspective view of one of the adjusting-blocks 20 illustrated in Fig. 3. Fig. 6 is a sectional view of the mechanism for driving the carriage. Fig. 7 is a sectional view on the line 7 7, Fig. 1; and Fig. 8 is a side view illustrating one of the centering-arms and connections.

A A are two beams supported on suitable foundations on each side of a pit, forming the bed-plate upon which the lower part of the mechanism is mounted.

35 A' is the upper frame, supported on suitable standards A², secured at their lower ends to the beams A.

B is a vertical shaft mounted in a bearing a, situated between the beams A and having 40 its lower end resting in a step-bearing c on a frame C, hung from the under side of the beams A by legs C'. In one of the legs C' is a bearing c' for the driving-shaft B', which has a bevel-pinion b' at one end which meshes 45 with a bevel-wheel b², secured to the shaft B.

The driving-shaft B' is connected to the armature-shaft of an electric motor B² by gearing, as illustrated in Fig. 2^b, the motor in the present instance being mounted in a pit below the floor.

On the upper end of the shaft B is the head b, over which the plate is flanged. This head is made removable, so that heads of different sizes may be secured to the shaft.

Mounted in line with the shaft B is a cylinder E, having a plunger E', carrying a head e. This cylinder is secured to the upper frame or beam A', and the plunger can be adjusted so as to move its head e toward and from the head b of the shaft B and is for the purpose of 55 clamping the plate to be flanged onto the head b.

Mounted on the beams A, forming the bed-plate, are two slides F and G. The slide F carries a vertical pin f, on which is mounted 60 the roller f', over which the plate is flanged. This roller can be moved toward and from the head b by shifting the slide F. On each side of the slide is a lug f², through which passes a screw F', mounted in bearings on the 65 side of the bed-plate, so that on turning the screws the slide can be adjusted.

On the slide G is a segmental guideway G', in which is a carrier G², and mounted in bearings on the carrier is a flanging-roller g, which 70 can be so manipulated as to turn the edge of a plate clamped between the heads over the roller f'. The slide G can be moved by means of screws G³ G³, Fig. 2^a, which have 75 their bearings in the bed-plate A and pass 80 through threaded lugs on the under side of the slide.

The carrier G² is turned in the segmental guideways G', in the present instance by a shaft g², having a pinion g³, which meshes 85 with a segmental gear g' on the carrier G². The shaft g² in turn is geared to a driving shaft G⁴ by bevel-gears g⁴ g⁴. This shaft G⁴ in the present instance is rectangular in cross-section and passes through a rectangular 90 opening in the hub g⁵ of a sprocket-wheel g⁶. This hub is mounted in a bearing g⁷ and flanged, so that it will remain in position in the bearing while the shaft G⁴ slides with the carriage G. The shaft in some instances 95 may be round and have a spline cut therein to receive a key on the hub, so that it can slide freely through the hub, but must turn with it. The sprocket-wheel g⁶ is geared to a wheel g⁷ on the armature-shaft of an electric 100

motor G^5 by a chain g^8 . The motor is mounted in a pit below the level of the floor, as illustrated in Fig. 1.

The carrier G^2 is made as clearly shown in Figs. 3 and 4. The part H has a segmental rib h on each side, adapted to the segmental guide in the portion G' . The part H is recessed to receive the sliding part H' , which has bearings h' for the spindle of the roller g . The parts H and H' each have a double bevel h^2 and h^3 , respectively, and mounted between the two parts are tapered blocks $I\ I$ of the form clearly shown in Fig. 5. These blocks have a rib at each corner, which enter undercut grooves in the parts $H\ H'$, thus coupling the part H' to the part H , but allowing the latter to be adjusted.

Passing through the blocks $I\ I$ is a right and left handed screw I' , mounted in sliding bearings $i\ i$. The screw is provided with a handle i' , by which it can be turned so as to shift the blocks toward or from each other to regulate the position of the roller g .

The mechanism for moving the screws F' and G^3 by power is constructed as follows: J is an electric motor mounted on a bracket a' , projecting from the side of one of the uprights A^2 . The shaft of this motor is belted to a shaft J' by a chain belt j , which passes around the wheels $j'\ j^2$. This shaft has two gear-wheels $k\ k'$. The wheel k meshes with a pinion k^2 , loose on a shaft K , and the wheel k' meshes with a pinion m , loose on the extended hub m' of a wheel M .

Each of the pinions k^2 and m have clutch-teeth at one side, and splined to the shaft K is a clutch k^3 , and splined to the hub M' is a clutch m' , so that on throwing either of the clutches into operative position either one or both parts K and M' will be driven by the motor.

Keyed to the shaft K is a gear-wheel K' , which meshes with pinions k^4 on the ends of the screw-shafts $G^3\ G^3$, which control the movement of the carriage G , and the wheel M meshes with pinions $m^2\ m^2$ on the ends of the screw-shafts $F'\ F'$, which control the movement of the carriage F .

On the clutch m' is a hand-wheel m^3 , and on the end of the shaft K is keyed a hand-wheel k^5 , so that either set of screw-shafts can be turned by hand, if desired. The clutches are shifted in the present instance by levers m^4 and k^6 , arranged to be locked to segments carried by the frame of the machine.

In order to center the plate in the machine, I provide four centering-slides N , Figs. 2^a and 8, which have arms N' extending above the floor and in line with the plate to be flanged, so that the vertically-arranged rollers n are in line with the plate, which is mounted on the head b .

Each slide N is mounted on rods $n'\ n'$, sup-

ported by bearings $n^2\ n^2$. The rods are preferably rectangular in cross-section, as shown, and between each pair of rods is a screw-shaft N^2 , which passes through a threaded lug n^3 on the under side of the slide N . On the inner end of each screw N^2 is a bevel-pinion p , which meshes with a bevel-wheel P , mounted loosely on the vertical shaft. This wheel is driven by a power-shaft P' , Fig. 2^a, which has a pinion p' , meshing with said wheel, and at the opposite end of the shaft is a gear-wheel p^2 , which meshes with a pinion on the armature-shaft p^3 of the motor P^2 . When the shaft P' is set in motion, all the screws are driven, causing all the slides N to travel toward or from the center of the machine.

The operation of the machine is as follows: If a plate is to be flanged, it is heated to the proper degree, then placed between the heads b and e , the centering device is set in motion, and as the slides N travel toward the center of the machine they adjust the plate until it is central. Then the head e is lowered and the plate is firmly clamped to the head b , after which the arms are withdrawn. The slide F is then adjusted to the proper position, as is also the slide G . Then the motor G^5 is set in motion to turn the carrier of the flanging-roller g , which as it travels in the arc of a circle turns down the edge of the plate as the plate is rotated, forming a flange over the anvil-roller f' . After the flange is formed the slide G is backed off, as is also the head e , after which the flanged plate can be removed from the machine.

All the parts are driven by electric motors, there being in the present instance a motor for each special train of mechanism.

I claim as my invention—

1. The combination in a flanging-machine, of a head, means for driving said head, means for clamping a plate to the head, a carriage, means for adjusting the carriage toward and from said head, said carriage having a segmental guideway, a carrier mounted therein, a flanging-roller on the carrier, a segmental gear on the carrier, a transverse shaft having a pinion meshing with the gear, a longitudinal shaft geared to said transverse shaft and arranged to travel with the slide, and a wheel through which the shaft slides and by which it is driven, and a motor for driving said wheel, substantially as described.

2. The combination in a flanging-machine, of a head, means for turning said head, means for clamping a plate to the head, a carriage, a segmental guideway on said carriage, a carrier mounted therein, said carrier being made in two parts one adjustable in respect to the other, a flanging-roller carried by the adjustable portion of the carrier, each portion of the carrier having double tapered portions,

wedge-blocks mounted between the portions of the carrier and arranged to travel on the tapered portions thereof, a right and left hand screw for moving the wedge-blocks toward and from each other, the said screws passing through slots in one of the portions of the carrier so as to freely move with the wedge-blocks, substantially as described.

3. The combination in a flanging-machine, 10 of a head, means for driving said head, means for clamping a plate to the head, a carriage, a segmental guideway in the carriage, a carrier mounted in the guideway, said carrier being made in two parts, one adjustable in respect 15 to the other, a roller carried by the adjustable part, each part having a double taper, the tapered portions of the parts facing each other, bevel-blocks mounted between the two parts and acting on the tapered surfaces, 20 grooves in each portion of the carrier, flanges on the blocks engaging the grooves, and means for moving the blocks toward and from each other, substantially as described.

4. The combination in a flanging-machine, 25 of a head, means for driving said head, means for clamping a plate to the head, two carriages mounted on the frame of the machine, an anvil-roller carried by one carriage, a segmental guideway mounted in the other carriage, a carrier mounted in said segmental guideway, a flanging-roller on the carrier, two sets of screws, one set actuating the anvil-roller carriage and the other the flanging-roller carriage, a shaft at one end of the machine, a wheel keyed to the shaft meshing 35 with the pinions on the screw-shafts of the flanging-roller carrier, a clutch on said shaft, a pinion loose on the shaft and arranged to be engaged by the clutch, a power-shaft, a wheel 40 on said power-shaft meshing with said pinion, a hub loose on the shaft having a gear-wheel meshing with pinions on the screw-shafts governing the movement of the anvil-carriage, a clutch on said hub, a pinion loose 45 on the hub and arranged to be engaged by the clutch, and a gear-wheel on the power-shaft meshing with the said pinion, substantially as described.

5. The combination in a flanging-machine, 50 of a head, means for driving said head, means for clamping a plate to the head, two carriages mounted on the frame of the machine, an anvil-roller on one carriage, a segmental guideway mounted in the other carriage, a carrier mounted in said segmental guideway, a flanging-roller on the carrier, two sets of screws, one set actuating the anvil-roller carriage and the other the flanging-roller carriage, a shaft at one end of the machine, a wheel keyed to the shaft meshing 55 with pinions on the screw-shafts of the flanging-roller carrier, a clutch on said shaft, a pinion loose on the shaft and arranged to be

engaged by the clutch, a power-shaft, a wheel on said power-shaft meshing with said pinion, a hub loose on the shaft having a gear-wheel meshing with pinions on the screw-shafts governing the movement of the anvil-carriage, a clutch on said hub, a pinion loose on the hub and arranged to be engaged by 65 the clutch, a gear-wheel on the power-shaft meshing with the said pinion, with a hand-wheel on the said clutch and a hand-wheel on the shaft upon which the clutch is mounted, substantially as described.

6. The combination in a flanging-machine, of a head, means for driving said head, means for clamping a plate to the head, a frame, rods radiating from the frame, slides on said rods, each slide having an arm extending to a 80 point in line with the head, a screw-shaft for actuating the slide, a pinion on the end of the screw-shaft, a gear-wheel loosely mounted on the shaft carrying the head, and a motor for driving said wheel, substantially as described.

7. The combination in a flanging-machine, of a frame, a vertical shaft mounted therein, a head carried on the said shaft, means for driving the shaft, means for clamping a plate on the head, a series of radiating ways projecting from the frame of the machine, each way consisting of two rods, a carriage mounted in each way having an arm in line with the head, a radiating screw-shaft for each way and engaging the slide, each screw having a 90 pinion at its inner end, a gear-wheel loose on the shaft meshing with the pinions of the screw-shafts, a driving-shaft having a pinion meshing with said gear-wheel, and a motor for driving said shaft, substantially as de- 95 100 scribed.

8. The combination in a flanging-machine, of a frame, a vertical shaft, a head carried by said shaft, means for clamping a plate to the head, means for flanging the plate, four radiating slideways, each consisting of two rods, a slide mounted on each pair of said rods, a radiating screw mounted between each pair of rods and actuating the slide, a bevel-pinion on each screw, a bevel-wheel loosely mounted on the vertical shaft, and meshing with the pinions, a power-shaft having a bevel-pinion meshing with the bevel-wheel, and means for driving said shaft, substantially as described.

9. The combination in a flanging-machine, of a frame, a vertical shaft, a head on said shaft, means for clamping a plate on the head, two carriages mounted on the frame, an anvil-roller on one carriage, a segmental guideway on the other carriage, a carrier mounted in said guideway, a flanging-roller on the carrier, a squared driving-shaft projecting rearwardly from the carriage and geared to turn the carrier in the segment, an electric motor 120 for driving said squared shaft, two sets of

4
screw-shafts, one set of screw-shafts arranged to move the anvil-roller carriage, the other set of screw-shafts arranged to move the flanging-roller carriage, a motor, gearing and clutch mechanism between the said motor and the said screw-shafts so that either one or both of the screw-shafts can be thrown into action, a gear-wheel on the vertical shaft carrying the head, a driving-shaft having a

motor for imparting motion to said driving-shaft, substantially as described.

In testimony whereof I have signed my name to this specification in the presence of two subscribing witnesses.

LOUIS N. McCARTER.
